(57) **CLAIM**

The ornamental design for a bandage, as shown and described.

DESCRIPTION

FIG. 1 is a perspective front view of a bandage;
FIG. 2 is a front elevation view of the bandage;
FIG. 3 is a rear elevation view of the bandage;
FIG. 4 is a left elevation view of the bandage; the right elevation view being a mirror image thereof;
FIG. 5 is a top elevation view of the bandage; and,
FIG. 6 is a bottom elevation view of the bandage.
The hexagonal pattern on the central portion of the bandage and the hatching texture on the opposing outer portions of the bandage form no part of the claimed design.
